UNITED STATES PATENT OFFICE.

HENRY L. F. BUSWELL, OF GLOUCESTER, MASSACHUSETTS, ASSIGNOR TO JOHN HAYS HAMMOND, JR., OF GLOUCESTER, MASSACHUSETTS.

SYSTEM FOR SALVO FIRING OF TORPEDOES.

Application filed November 10, 1917, Serial No. 201,346. Renewed December 30, 1921. Serial No. 526,034.

To all whom it may concern:

Be it known that I, HENRY L. F. BUSWELL, a subject of the King of Great Britain, and a resident of the city of Gloucester, 5 in the county of Essex, State of Massachusetts, U. S. A., have invented certain new and useful Improvements in Systems for Salvo Firing of Torpedoes, of which the following is a specification.

10 Some of the objects of this invention are to provide a system for firing salvos of torpedoes in which the torpedoes may be simultaneously discharged in various directions from a torpedo boat and may be automatically caused to proceed ultimately upon parallel courses towards a target; and to provide other improvements as will appear hereinafter.

In the accompanying drawings, Fig. 1 20 is a diagrammatic top plan view of a torpedo boat provided with a system constructed in accordance with this invention for discharging salvos of torpedoes and showing the course of a target and corresponding 25 courses upon which the torpedoes may be caused to proceed; Fig. 2 is a top plan view of a device constructed in accordance with this invention and forming a part of this improved system; Fig. 3 is a diagrammatic 30 view of a system constructed in accordance with this invention; Figs. 4 and 5 are fragmentary side elevations of portions of the system shown in Fig. 3; Fig. 6 is a top plan view of a modified device constructed in accordance with this invention; and Fig. 7 35 is a diagrammatic top plan view showing a torpedo boat provided with a system constructed in accordance with this invention and showing the course of a target and 40 courses which the torpedoes may be caused to follow under certain conditions.

Referring to the drawings, one embodiment of this invention comprises a torpedo boat 10 which is provided in its bow with a 45 fixed torpedo-tube 11 extending longitudinally thereof and arranged to discharge a torpedo 12. The torpedo boat 10 is also provided with two oppositely disposed torpedo-tubes 13 and 14 fixed upon the torpedo 50 boat 10 substantially midway between the bow and the stern of the boat and arranged to discharge two torpedoes 15 and 16 in opposite directions respectively and substantially along a line perpendicular to the longitudinal axis of the boat. The boat 10 is

also provided with two parallel torpedo-tubes 17 and 18 fixed upon the boat adjacent its stern and arranged to discharge two torpedoes 19 and 20.

In this improved system each of the torpedo-tubes 11, 13, 14, 17 and 18 is provided with a torpedo having a hull of any suitable construction and arranged to be propelled automatically by suitable means and to be steered by a rudder 21 (see Fig. 3) which is 60 mounted upon an upright rudder post 22 to oscillate about an upright axis fixed with respect to the torpedo.

For predirecting each torpedo to proceed either upon a straight line towards the 70 target or upon a broken course consisting of two straight portions which meet at a predetermined angle and at a variable but predetermined distance from the torpedo boat the rudder 21 of each torpedo is arranged to 75 be oscillated by a crank arm 25 rigid with the rudder 21 and pivotally connected at its free end to one end of a connecting rod 26, the other end of which is pivotally connected to the outer end of the piston-rod 27 80 which is arranged to reciprocate in a cylinder 28 arranged within and fixed with respect to the torpedo. Within the cylinder 28 is arranged to reciprocate a piston 29 which is rigidly secured to the inner end of the piston-rod 27. The piston 29 is controlled 85 pneumatically in a well known manner by means of a valve 30 which includes a fixed cylindrical valve casing 31 which is provided with a valve-stem 32 extending longitudinally therethrough and having mounted thereon two pistons 33 and 34 which control and normally close two outlets leading into two pipes 35 and 36 which lead into the opposite ends of the rudder cylinder 28. 90 The valve casing 31 is arranged to be supplied centrally with compressed air from a supply pipe 38 which leads from a tank 40 or other source of compressed air. The valve-stem 32 extends in opposite directions 95 from the casing 31 and its opposite ends are arranged to reciprocate in and from cores for two fixed solenoids 45 and 46.

For controlling the solenoids 45 and 46 to cause the rudder 21 to be actuated in 100 such a manner as to cause the torpedo to be steered first in one direction for a predetermined distance or time, and then in a different direction, a gyroscope 60 is provided. Above the gyroscope 60 is a nor- 110

mally vertical shaft 61 which is arranged to rotate relative to the torpedo in bearings 62 fixed with respect to the torpedo. Surrounding the shaft 61 and coaxial therewith, are a lower or primary azimuth ring 65 and an upper or secondary azimuth ring 66. The upper or secondary azimuth ring 66 is rigid with a spider 67, which snugly surrounds but which is rotatable with respect to and held against movement longitudinally of the vertical shaft 61. Secured within the upper ring 66 but insulated therefrom are two approximately semi-circular segmental conductors 68 and 69, which are arranged to be slidably engaged successively by a yielding brush 70 carried by the outer end of a conducting arm 71, which is rigidly secured to but insulated from a vertical shaft 61.

For rotatably adjusting the upper azimuth ring 66 with respect to the torpedo, the outer surface of the ring 66 is provided with gear teeth 75 which are engaged by a pinion 76 which is arranged to be rotated with respect to the torpedo about a normally vertical axis fixed with respect to the torpedo by means of an electrical motion repeating device 77 of any well known or suitable construction, which is mounted upon the torpedo boat outside of the torpedo and which acts upon the repeating device 77 through a four wire cable 79 including a return wire 80 arranged to be energized by a battery 81. The wire 79 is connected to a plug 82 which separates when the torpedo leaves the tube. The transmission device 78 is arranged to be actuated by means of a pinion 85, which is arranged to be rotated by a gear 86 which is rigid with a normally vertical spindle 87 which is held against longitudinal movement and is arranged to be rotated about an axis fixed with respect to the torpedo boat and to be rotated by means of a telescope 90 which is mounted upon the upper end of the spindle 87 to rotate with respect thereto about an axis fixed with respect to the spindle 87 and extending normally horizontally. The lower or primary azimuth ring 65 is normally held in a fixed position with respect to the torpedo in any suitable manner, but may be rotatively adjusted manually to any desired position. Arranged within the ring 65 and secured thereto but insulated therefrom are two approximately semi-circular segmental conductors 95 and 96 which are arranged to be slidably engaged successively by a yielding brush 97 carried by the free end of an arm 98 which is rigidly secured but insulated from the vertical shaft 61.

For rendering the primary and secondary azimuth rings 65 and 66 successively operative to control the direction of movement of the torpedo, a time switch 110 is provided which includes a fixed disc 111 which

loosely surrounds and is coaxial with a spindle 112 which is arranged to be rotated at a predetermined rate by a clock mechanism 113 or any other suitable mechanism. Secured to the disc 111 but insulated therefrom and coaxially with the shaft 112, are a comparatively short segmental contact 114 and a comparatively long segmental contact 115, and rigidly secured to but insulated from the shaft 112 is a switch arm 116, the outer end of which is arranged to engage slidably over the two segmental contacts 114 and 115 successively.

To permit a rotary adjustment of the shaft 112 without affecting the clock mechanism 113, the clock mechanism 113 is preferably arranged to actuate a short spindle 117 which is arranged in longitudinal alignment with the shaft 112, and which carries at its outer end a disc 118 which is normally pressed toward the shaft 112 by a spiral spring 119, but which is held against rotation with respect to its spindle 117, the disc 118 being thus normally pressed against a corresponding disc 120 which is rigid with the adjacent end of the shaft 112. When the shaft 112 is adjusted rotatably, as will appear hereinafter, the disc 120 carried by the shaft 112 rotates with respect to the disc 118 carried by the spindle 117 and thus permits the shaft 112 to be rotatably adjusted without disturbing the clock mechanism 113.

The inner ends of the windings of the two solenoids 45 and 46 are connected by a conductor 125 with one pole of a battery 126, the other pole of which is connected by a conductor 127 to the switch arm 116 of the time switch 110. The outer end of the winding of the inner solenoid 45 is connected by a conductor 130 and branch conductor 131 to the two corresponding segmental conductors 96 and 69 of the primary and secondary azimuth rings 65 and 66, and the outer end of the outer solenoid 46 is connected by a conductor 132 and a branch conductor 133 to the corresponding segmental conductors 95 and 68 of the primary and secondary rings 65 and 66 respectively. The arm 98 of the primary ring 65 is connected by a conductor 135 to the comparatively long segmental contact 115 of the time switch 110, and the arm 71 of the secondary ring 66 is connected by a conductor 136 to the comparatively short contact 114 of the time switch 110.

For giving an initial adjustment to the switch arm 116 of the time switch 110, the outer end of the shaft 112 which carries the switch arm 116 is arranged within the torpedo and in proximity to an opening 140 provided therefor in the outer shell 141 of the torpedo, and is arranged to be detachably engaged by the inner end of a longitudinally movable shaft 142 which is surrounded by a gear 143 rigid therewith, and

which is engaged by a pinion 144 which is arranged to be rotated about a fixed axis by any suitable electrical repeating mechanism 145 which is arranged to be actuated 5 by any suitable electrical transmission mechanism 146 fixed upon the torpedo boat and arranged to act through a four wire cable 147 having a return wire 148 arranged to be energized by a battery 149. The transmission device 146 is arranged to be actuated 10 by a pinion 156 which is arranged to be actuated by a gear 157 which is arranged to rotate about a fixed axis upon a shaft 158 which carries an index 160 which is arranged 15 to cooperate with a stationary dial 161 provided marginally with suitable graduations.

The shaft 142 is held against rotation with respect to the shaft 112 by means of a diametrical lug 165 which is integral with the 20 inner end of the shaft 142 and which engages in a corresponding recess provided therefor in the outer end of the shaft 112. After the shaft 112 has been given an initial rotary adjustment by the repeating device 145, and 25 before the torpedo 141 is fired or discharged from its tube, the shaft 142 is moved longitudinally outwardly to free the inner end of the shaft 142 from the torpedo.

To initiate the operation of the clock 30 mechanism 113 of the time switch 110, as a result of the withdrawal of the shaft 142 from the shell 141 of the torpedo, a bell crank lever 175 is arranged within the torpedo to swing on a pivot 176 about a fixed 35 axis, and one end of the bell crank lever 175 is arranged to be pressed by a spiral spring 177 normally outwardly against the inner end of the shaft 142 when the shaft 142 is in an operative position, and the other end 40 of the bell crank lever 175 is arranged to hold the clock mechanism 113 against operation when the shaft 142 is in its operative position, and to release the clock mechanism 113 when the shaft 142 is withdrawn to permit the bell crank lever 175 to swing through 45 a small arc in a clockwise direction, as shown in Fig. 5.

In the operation of this improved system, when a target 200 is moving along a line 50 or course 201 extending across the longitudinal axis of and in front of the torpedo boat 10 and is in a position included within an angle of about thirty degrees formed between two intersecting lines one of which 55 coincides with the longitudinal axis of the torpedo boat 10, and the other of which extends through the center of the torpedo boat and the center of the targets, all five of the torpedoes 12, 15, 16, 19 and 20 may be pre- 60 directed in such a manner that when simultaneously fired or launched from their tubes 11, 13, 14, 17 and 18, the torpedoes will ultimately assume and proceed upon parallel equi-spaced courses intersecting the line of 65 movement 201 of the target 200 at points

spaced apart at predetermined but variable distances.

For instance, if as shown in Fig. 1, the torpedo boat 10 is proceeding along a line 205 towards the target 200 which is proceeding upon a course 201 and which is positioned in a line 206 extending through the center of the torpedo boat 10 and making an angle of less than thirty degrees with the line 205 containing the longitudinal axis of the 70 torpedo boat 10, and it is desired to discharge the torpedoes 12, 15, 16, 19 and 20 so that they will ultimately proceed approximately along parallel equi-spaced courses 206', 207, 208, 209 and 210 respectively intersecting the line of movement 201 of the target 200 in points 214, 215, 216, 217 and 218 respectively which are spaced apart at equal and predetermined distances 220 measured along the direction of movement 201 of the 75 target 200, the bow torpedo 12 should be predirected so that it will seek and proceed upon a course 206' but slightly displaced from the line 206 extending from the boat 10 through the target 200, and two amidship torpedoes 80 15 and 16 should be predirected so that they would travel in opposite directions along the lines 225 and 226 extending in a direction of the corresponding torpedo tubes 13 and 14 until the torpedoes 15 and 16 reach the 85 points 227 and 228, and then be diverted from their courses and caused to assume and travel along the courses 207 and 208 parallel to the course 206' of the bow torpedo 12. The stern torpedoes 19 and 20 should be predirected in this case to proceed in opposite 90 directions along the lines 230 and 231 extending at right angles to the torpedo tubes 17 and 18 until the torpedoes 19 and 20 reach the points 232 and 233 at predetermined distances from the torpedo boat 10, and would then be caused to assume or travel upon the courses 209 and 210 parallel to the courses 206', 207 and 208 of the torpedoes 12, 15 95 and 16.

To facilitate the setting of the time switch 110 to cause the amidship and stern torpedoes to first travel outwardly from the torpedo boat along the lines perpendicular to the longitudinal axis of the torpedo boat 110 and through the required distances, this invention provides a device, shown in Fig. 2, which includes a fixed flat base 250 and a bar 251 which is movable towards and away from the base 250, and which is connected 115 to the base 250 by two pairs of links 251' and 252, each pair of which are pivotally connected, and are pivotally connected to the fixed base 250 and to the bar 251 respectively, and connected by the bar 253 so as to cause the bar 251 to remain always parallel to the base 250 as the bar 251 is being moved towards or away from the base 250. The bar 251 is provided with two parallel scales 120 255 and 256 rigid therewith and extending 125 257 and 258 respectively, and the base 250 is provided with two parallel scales 259 and 260 rigid therewith and extending 130 261 and 262 respectively.

perpendicularly thereto, and in a direction away from the fixed base 250. The inner edges of these two scales 255 and 256 are provided with suitable graduations 257 and 258. Between the two scales 255 and 256 is located a fixed pivot 260 which extends in a direction perpendicular to the plane of the scales 255 and 256, and which is surrounded by a suitable graduated dial 261 rigid therewith. Mounted upon the fixed pivot 260 to rotate with respect thereto about an axis, is an arm 262 which extends in opposite directions from the pivot 260, and the opposite ends of which are arranged to engage slidably over the two scales 255 and 256 respectively. Extending slidably over the arm 262 is a spacing bar 265 which is arranged to oscillate with respect to the movable bar 251 about a pivot 266 fixed with respect to the movable bar 251, and extending through one end of the spacing bar 265. The spacing bar 265 is provided with an elongated slot 267 extending longitudinally and centrally thereof, and in which the fixed pivot 260 snugly but slidably engages. The distance between the inner graduated edges of the two scales 255 and 256 is taken as representing twice the distance between the amidship torpedo tubes 13 and 14 and the stern torpedo tubes 17 and 18, and the pivot 266 upon which the spacing bar 265 is mounted is arranged midway between the inner edges of the two scales 255 and 256. Extending from the fixed pivot 260 and perpendicular to the bar 251 is a scale 268, the graduations of which are drawn to one-half the scale of the graduations 257 and 258.

In adjusting the device just described, the movable bar 251 is moved towards or away from the stationary base 250 until the distance between the fixed pivot 260 and the pivot 266 carried by the bar 251 is proportional to twice the desired "dispersion" or predetermined distance 220 between the points where it is proposed to have the courses of the torpedoes intersect the line of movement of the target 200. The spacing arm 265 is also swung about the fixed pivot 260 to set the arm in such a position that the longitudinal axis of the arm 265 will make an angle 270 with a line drawn through the fixed pivot 260 and parallel to the movable bar 251 which is equal to the known angle 25 between the direction of motion of the torpedo boat 10 and the course of the target 200, for instance, equal to the angle 275 between the line 205 and the line 201 of Fig. 1. The arm 262 is rotated into such a position of adjustment that its longitudinal axis makes an angle 276 with a line drawn through the fixed pivot 260 parallel to the bar 251, which is equal to the angle 277 between the line of movement 205 of the torpedo boat 10 and a line 206 drawn through

the torpedo boat 10 and the target 200. When the parts are thus set, the distances which the two stern torpedoes 19 and 20 must travel, in opposite directions measured from the center line of the torpedo boat 10 in order to have the torpedoes 19 and 20 reach the points 232 and 233 in which the torpedoes are to turn towards the line of movement of the target 200, will be marked off by the opposite ends of the arm 262 upon the two scales 255 and 256 respectively. The distances which the two amidship torpedoes 15 and 16 must travel from the longitudinal axis of the boat in opposite directions before reaching their turning points 227 and 228 are equal and read off from the scale 268 where the upper edge of the bar 251 cuts the scale 268. All of these distances may be quickly determined from the scales 255, 256 and 268, and the predirecting mechanism of the torpedoes may be set accordingly.

For the convenience of the operator, instead of graduating the scales 255, 256 and 268 in units of length, these scales may be graduated in units of time which it will take for the torpedoes to travel at a given rate over the distances indicated upon the scales 255, 256 and 268 by the arm 262.

After having thus determined the distances or units of time through which the torpedoes must travel in opposite directions respectively from the torpedo boat 10 before reaching their turning points 227 and 228, 232 and 233, the time switch 110 of each torpedo is set accordingly by rotating its arm 160 through a corresponding number of degrees as read upon its dial 161. The motion of the arm 160 is transmitted through the transmitter 146 to the repeater 145, and causes the rotation of the switch arm 116 from an initial position shown in dotted lines through a corresponding number of degrees without interfering with the operation of the corresponding clock mechanism 113. Each switch arm 116 is thus set in such a position that it will take the switch arm 116 under the action of the clock mechanism 113 such a period of time to be rotated into engagement with the relatively short contact 114 as will permit the torpedo to travel at a predetermined rate from the torpedo boat to the point of turning of the torpedo, whereupon the switch arm 116 having reached the comparatively short contact 114 will shift the control of the torpedo from the stationary azimuth ring 65 (see Fig. 3) to the azimuth ring 66 which has been set by aiming the telescope upon the target 200. After each time-switch 110 has been thus set, and after the movable azimuth ring 66 of each torpedo has been set by sighting the corresponding telescope 90 upon the target 200, the torpedoes may be simultaneously discharged from their tubes in any suitable manner, and the tor-

pedoes will then proceed upon the courses, for instance, as shown in Fig. 2 as hereinbefore described.

In the case of the torpedoes 19 and 20 the azimuth rings 65 are set at 90° to the arms 98 so that the torpedoes 19 and 20 will turn at right angles as soon as they leave the tubes and travel on the courses 230 and 231 respectively until they reach the points 10 232 and 233.

If, as shown in Fig. 7, the torpedo boat 10 is proceeding along a line 300 extending in a direction of the longitudinal axis of the boat 10, and the target 200 is moving along 15 a line 301 and is in a line 302 drawn through the target and through the center of the torpedo boat 10 which makes an angle 305 greater than thirty degrees with the longitudinal axis of the torpedo boat, it would 20 probably be found desirable to use a modified auxiliary device for determining the angle at which the indicator 160 of the time switch 110 of each torpedo should be set in order to have the torpedoes proceed ultimately upon parallel courses 306, 307 and 308 which intersect the line of movement 301 of the target 200 at points 309, 309' and 309'' respectively which are spaced apart at approximately equal predetermined distances. 25 In this case, the modified auxiliary device shown in Fig. 6 and forming a part of this invention might be utilized. This modified device includes a rigid frame, comprising a central rigid beam 310, and two aligned arms 311 and 312 rigid with the beam 310 and extending in opposite directions therefrom. Carried by the central beam 310 is a lever 315 which is arranged to swing about a fixed axis with respect to the beam 310 upon 30 a pivot 316 extending through one end of the lever 315, and secured to the central beam 310 at a point spaced upon one side of the two arms 311 and 312 at a distance proportional to half the length of the ship. 35 Rigidly secured to the central beam 310 and arranged coaxially with the pivot 316 is a dial 317 which is marginally graduated in degrees to permit of the convenient adjustment of the lever 315 at any desired angle 40 with respect to the central beam 310, the lever 315 being provided with an opening 320 through which the graduations upon the dial 317 may be read, and being provided with a central mark 321 adjacent the opening 320 to be used as a guide in rotatively 45 adjusting the lever 315. The lever 315 is provided with a slot 325 extending longitudinally and centrally thereof, and snugly but slidably arranged in this slot 325 is a pivot 326 upon one end of which is rigidly secured one end of a movable arm 327, and upon the other end of the pivot 326 is threaded a nut 328 whereby the pivot 50 may be clamped securely in any position 60 of adjustment longitudinally of the lever 315.

Snugly surrounding the central beam 310 and slidably adjustable longitudinally thereof, is a slider 330 which has rigidly secured thereto a dial 331 which is graduated marginally in degrees. Mounted upon the slider 70 330 to rotate with respect thereto about an axis fixed with respect to the slider and extending through the center of the dial 331, is a carrier 335 which is provided with an opening through which snugly but slidably 75 extends the arm 327. The arm 327 is provided with one edge 336 which is straight throughout its length and which is in a line which intersects the axis of the pivot 326 which supports one end of the arm 327, and 80 also the axis about which the carrier 335 rotates with respect to the dial 331. The central beam 310, each of the stationary arms 311 and 312, and the swinging lever 315 are each provided with suitable graduations extending along one edge thereof in each case, and which are laid off in units of length. In using the modified device shown in Fig. 6, the pivot 326 is adjusted along the slot 325 until the distance between the axis of the 90 pivot 326 and the axis of the pivot 316 as indicated by the graduations on the lever 315 is proportional to the desired dispersion or distance between any two succeeding points in which the desired ultimate courses 306, 95 307 and 308 of the torpedoes cross the course 301 of the target 200. The pivot 326 is then held against movement longitudinally of the lever 315, and the lever 315 is rotatably adjusted until it makes an angle 100 340 with the beam 310 which is equal to the angle 341 between the line of movement of the target 301 and the line of movement 300 of the torpedo boat 10. The movable arm 327 is then rotatably adjusted about the pivot 105 326 by moving the slider 330 either in one direction or in an opposite direction until the angle 345 which the arm 327 makes with the central beam 310 is equal to the hereinbefore described angle 305 between a 110 line drawn through the target 200 and the center of the torpedo boat 10, and the line of movement 300 of the torpedo boat 10. When the parts of the device shown in Fig. 6 have been thus adjusted, the distance 350 115 which one of the stern torpedoes 20 will have to go in a direction perpendicular to the longitudinal axis of the torpedo boat 10 before it reaches the point 351 where it will be diverted into its ultimate course 308, may 120 be read upon the graduations upon the fixed arm 311, the distance being indicated at the point where the movable arm 327 crosses the fixed arm 311. The distance 355 which the bow torpedo 12 must move in the direction 125 of the longitudinal axis of the torpedo boat 10 before the bow torpedo 12 reaches the point 356 where it must be diverted from its course to follow its ultimate course 306, 130 may be read upon the graduations on

the central beam 310, the distance being indicated by the point where the straight edge 336 of the movable arm 327 crosses the central line of the central beam 310 or the line connecting the longitudinal axis of the pivot 316 with the axis of oscillation of the rotatable carrier 335. Having thus determined these distances 350 and 355, the indicators 160 of the stern torpedo 20 and the bow torpedo 12 may be adjusted accordingly, as hereinbefore described, to cause those torpedoes to follow the courses indicated in Fig. 7.

Although only a single automatic steering system constructed in accordance with this invention has been shown herein, and although only two forms of auxiliary devices constructed in accordance with this invention for facilitating the adjustment of the steering system have been shown, it is to be understood that the invention is not limited to any specific steering system or to any specific auxiliary devices for adjusting the system, but might be applied in the various steering systems and adjusted with the aid of any suitable auxiliary device without departing from the spirit of the invention or the scope of the appended claims.

Having thus fully described this invention, I claim:

30. 1. In a system of salvo-firing, a vessel, a plurality of torpedoes carried thereby, means to discharge said torpedoes in different directions, and means operable after the discharge for causing all of said torpedoes to assume substantially parallel paths moving in the same direction to intersect the path of a target common to all of said torpedoes.
40. 2. In a system of salvo-firing, a vessel, a plurality of torpedoes carried by said vessel, means to discharge said torpedoes in different directions, and means operable after the discharge for causing all of said torpedoes to move in the same general direction to intersect the path of a moving target common to all of said torpedoes.
50. 3. In a system of salvo-firing, a vessel, a plurality of torpedoes carried by said vessel, means to discharge said torpedoes so that each proceeds along a different predetermined course, auxiliary devices arranged respectively to determine the distance each torpedo continues on its predetermined course, and means operable by said auxiliary devices for causing said torpedoes to finally move in parallel paths in the same direction to intersect the path of a moving target common to all of said torpedoes.
60. 4. In a system of salvo-firing, a vessel, a plurality of torpedoes carried by said vessel, means to discharge said torpedoes so that each proceeds along a different predetermined course, auxiliary devices arranged respectively to determine the distance each

torpedo continues on its predetermined course, and means operable by said auxiliary devices for causing said torpedoes to finally move in the same general direction to intersect the path of a moving target common to all of said torpedoes.

5. In a system of salvo-firing, a vessel, a plurality of torpedoes carried by said vessel, means to discharge one torpedo along a course toward a target, means to discharge another torpedo along a course away from said target, and means operable after a predetermined interval to change the course of said second torpedo to direct it in the same general direction as the first torpedo. 80

6. In a system of salvo-firing, a vessel, a plurality of torpedoes carried by said vessel, means to discharge one torpedo along a course toward a target, means to discharge another torpedo along a course laterally 85 with respect to the course of said first torpedo, means to discharge a third torpedo along a course substantially opposite to the course of said first torpedo, and means operable after a predetermined interval to change 90 the courses of the second and third torpedoes respectively to direct them in the same general direction as said first torpedo.

7. In a system of salvo-firing, the combination of a vessel, a plurality of projectiles, 95 means positioned upon said vessel for discharging said projectiles therefrom in different directions, and means operable after the discharge for rectifying the direction of movement of the projectiles into substantially parallel paths intersecting the path of a target common to all of said projectiles. 100

8. In a system of salvo-firing, the combination of a vessel, a plurality of projectiles, means positioned upon said vessel for discharging said projectiles therefrom in different directions, and means operable after the discharge for rectifying the direction of movement of the projectiles into a single predetermined direction intersecting the 110 path of a target common to all of said projectiles.

9. In a system of salvo-firing, a vessel, a plurality of projectiles, means positioned upon said vessel for discharging said projectiles so that each proceeds along a different predetermined course, auxiliary devices arranged respectively to determine the distance each projectile continues on its predetermined course, and means operable by said auxiliary devices for causing said projectiles to finally move in substantially parallel paths in the same direction to intersect the path of a moving target common to all of said projectiles. 115 120

10. In a system of salvo-firing, a vessel, a plurality of projectiles carried by such vessel, means to discharge at least one projectile along a course toward a target, means to discharge at least one other projectile along a 130

course away from said target, and means operable after a predetermined interval to change the course of said second projectile to direct it in the same general direction as the first projectile.

11. In a system of salvo-firing, a vessel, a plurality of projectiles carried by said vessel, means to discharge at least one projectile along a course toward a moving target, means to discharge at least one other projectile along a course away from said target, means operable after discharge to change the course of the second projectile into a direction substantially parallel to that of the moving target, and means operable after a predetermined interval to change the course of said second projectile to direct it in the same general direction as the first projectile.

12. In a system of salvo-firing, a vessel, a plurality of projectiles carried by said vessel, means to discharge at least one projectile along a course toward a moving target, means to discharge at least one other projectile along a course away from said target, means operable after the discharge of the projectile to divert its course into the same general direction as the target and means operable after a predetermined interval to change the course of said second projectile a second time to direct it in the same general direction as the first projectile.

13. In a system of salvo-firing, a vessel, a plurality of projectiles carried by said vessel, means to discharge at least one projectile along a course toward a target, means

to discharge at least one other projectile along a course laterally with respect to the course of said first projectile, means to discharge at least one additional projectile along a course substantially opposite to the course of said first projectile, and means operable after a predetermined interval to change the courses of the second and third projectiles respectively to direct them in the same general direction as said first projectile.

14. In a system of firing projectiles, the combination of a vessel, a plurality of projectiles arranged to be discharged from said vessel, and means operable after the discharge for modifying the direction of movement of the projectiles into a single predetermined direction intersecting the path of a target common to all of said projectiles.

15. In a system of salvo-firing, a moving target, a vessel moving in a direction to intersect the path of movement of the target, means to discharge at least one projectile along a course substantially parallel to the direction of movement of the vessel, means to discharge at least one other projectile along a course contrary in direction to the movement of the vessel, means operable after discharge to change the course of the second projectile to direct it in the same general direction as the vessel.

Signed at New York, in the county of New York and State of New York, this 5th day of November, A. D. 1917.

HENRY L. F. BUSWELL.
